United States Patent Office

Des. 216,278

Patented Dec. 9, 1969

216,278

EXHAUST GAS TEMPERATURE INDICATOR

William V. Simpkinson, 18145 Judy St., Castro Valley, Calif. 94546, and Jerome L. Kurz, 565 Willow Road, Menlo Park, Calif. 94025

Filed Mar. 27, 1968, Ser. No. 11,155

Term of patent 14 years

Int. Cl. D10—08

U.S. Cl. D52—6

FIG. 1 is an isometric view of an exhaust gas temperature indicator, showing our new design;

FIG. 2 is a front end view thereof;

FIG. 3 is a side elevational view thereof;

FIG. 4 is a rear end view thereof; and

FIG. 5 is an alternate form of the rear end of the design, it being understood that except for the rear end this embodiment is identical with the embodiment depicted in FIGS. 1-4.

We claim:

The ornamental design for an exhaust gas temperature indicator, substantially as shown and described.
